WALTER E. GORHAM, OF VERDUN, QUEBEC, CANADA

FOLDING HAND BASIN

Application filed October 15, 1928, Serial No. 312,643, and in Canada August 31, 1928.

This invention relates to new and useful improvements in folding wash basins and particularly to basins for use in railway cars and the like.

5. The principal objects of the invention are to provide a wash basin which can be folded into or against a wall without undue shock to the basin or its supporting mechanism; to provide means for automatically cutting 10 off the water supply when not in use, and to provide means for emptying the basin of its contents before it goes into the inoperative position.

According to my invention I provide a 15 wash basin mounted on suitable brackets pivotally secured by any suitable means to a wall. The hot and cold water connections are made to a special cut off cock which is so arranged that the water supply to the basin is cut off 20 when the basin is in its folded or inoperative position. The centre of the cock is arranged on the pivot centre of the basin brackets. The waste connection is also arranged so that the waste pipes will pivot about the pivot 25 centre. Locking means are provided to hold the basin against movement when in the operative position and said locking means are connected to the waste lever so that the water is drained from all parts of the basin before 30 it is folded. The basin is slidably connected to a panel which is pivotally connected to the wall of a car body or the like and means are provided for checking the movement of the basin in its closing or opening movement to 35 protect the basin mechanism against shocks.

In the drawings which illustrate my invention:—

Figure 1 is a plan view of my improved wash basin.

40. Figure 2 is a side elevation of the basin shown in Figure 1.

Figure 3 is a front view of the basin.

45. Figure 4 is an enlarged view of the air checking mechanism for cushioning the opening and closing movement of the basin.

Figure 5 is a sectional elevation of the stop cock.

50. Figure 6 is a plan view of the connection between the waste pipe from the basin and the elbow to the drain.

Referring more particularly to the drawings, 11 designates a hand basin of the usual type which is secured to a bracket 12 at the sides 13. The brackets are pivotally secured to supports 14 extending outwardly from the wall 15 of the car or the like. The pivot on one side may be the bolt 16 and on the other side a pin 33 may be used, said pin engaging with a recessed extension 17 from the waste pipe elbow 18. This extension holds the waste pipe at this point on the pivot centre. The basin has the usual faucets 19 and 20 for the flow into the basin and the faucet 21 for the dental pipe 22. The details of the faucets are not shown as they are of the usual construction. A waste lever 23 is also provided for controlling the discharge of water from the basin. The connections between the lever 23 and the waste pipe 24 are not shown. The waste pipe is connected to the bottom of the basin by means of the casting 25. The waste pipe 24 is provided with a connection 29 to the elbow 18. This connection will allow pivoting movement and is shown in detail in Figure 6. The waste pipe has rotatably mounted thereon an internally threaded nut 30, the threads of which engage with the threaded end 31 of the elbow 18. Between the adjacent ends of the elbow and the waste pipe a packing 32 is provided to make a watertight joint between them. The drain pipe 34 from the elbow extends downwardly and may be secured by any suitable means to the wall.

The elbow and drain pipe are held against movement but the connection 29 will allow pivoting movement between the waste pipe and the elbow. The water supply pipes 35 and 36 are secured to the car and are connected to a stop cock 37, details of which are shown in Figure 5. The hot water supply pipe 35 is connected to the cock casing 38 through the internally threaded aperture 39. The aperture 39 is adapted to register with the entrance 40 of a passageway 41 formed in the central conically shaped core 42 of the cock which has an externally threaded portion 43 extending beyond the end of the casing.

This portion 43 passes through a bracket 44 secured to the wall of a car body or the like

and is rotatably mounted therein and held in place by the nut 45. The passageway 41 extends through the portion 43 and registers with the hot water pipe connection 46, the outlet from which is controlled by a faucet. The cold water connection pipe 36 is connected to the internally threaded aperture 47 in the casing 38 which registers with the opening to a passageway 48 formed in the tapered or conically shaped core 42 of the cock. This passageway extends towards the end 49 of the core and is independent of the passageway 41. The end 49 is threaded externally and is connected by any suitable piping to the cold water faucets on the basin and dental section. The core is drawn into the casing by means of the nut 45. To form a watertight joint between the end 50 of the casing and the core, double glands 51 and 52 are provided. Gland 51 engages with the internally threaded portion 50 and a packing ring 53 is provided to prevent the water from leaking through between the gland 51 and the cock casing. The gland 52 engages with an internally threaded portion of the gland 51 and is adapted to expand the packing ring 54 by pressing it against a rib 55 formed in the said gland 51. The expansion of the packing ring 54 seals the joint between the gland and the end 49 of the core. This construction allows the core to rotate within the casing to bring the entrance to the passageways into and out of register with the supply pipe when the basin is in the operative or inoperative position. Figure 1 shows the basin in the operative position, that is, ready for use and in the open position. The waste lever 23 has a lever 56 connected thereto and adapted to move therewith. This lever is connected by a link 57 to the lever 58 secured to a spindle 59 rotatably mounted in the basin brackets and connected to a lever 60 and connecting rod 61 to a locking catch 62. The locking catch is pivotally secured to the basin brackets and its hooked end 63 projects upwardly through a slot 64 in the supports 14.

When the basin has water therein and the waste plug closed, the waste lever is in such a position that the hooked part of the locking lever engages with the edge of the slot in the support 14. When the waste lever is in the position to hold the plug in the open position, the hooked end is down clear of the support and the basin may be turned upwardly about the pivot. This arrangement ensures that the basin must be emptied before it is raised. The basin is provided at its front with a downwardly projecting arm 65 the end 66 of which is bifurcated and adapted to extend over the sides 67 of a cylinder 68, the sides of which are provided with guides adapted to receive guide blocks 69 pivotally attached by pins 70 to the bifurcated ends. These guides extend beyond the end 71 of the cylinder and are connected together and to

a piston rod 72. The piston rod extends into the cylinder and is provided with a piston 73. An air vent 74 is formed in the walls of the cylinder to regulate the discharge of air therefrom. The cylinder is secured to a tray 75 secured to the back 76 of a chair or panel which is hingedly attached to the support 14 by the hinges 77. The centre of the hinges is positioned below and in front of the basin pivot.

It will be seen that in operation the basin, when moved from its operative position shown in Figure 1 to its inoperative position against the wall, has its supply of water automatically cut off and it will also be seen that, before this movement can take place, the waste plug must open to release the lock or catch. This combination drain control and locking arrangement ensures that the basin must be emptied before it can be moved against the wall. The pipe connections for the water supply and discharge are arranged so that they pivot about the basin connection pipe. This arrangement allows the pipes to be connected without the necessity of using the flexible pipes or the like. To lessen the shock of closing and opening, the piston working in the cylinder cushions the movement. The cylinder being connected to the panel or chair back which operates on a pivot below and in front of the basin pivot makes the piston operate to cushion the movement of the basin against the air in the cylinder. The basin has a soap retaining recess 78 which is partially covered by a hood 79, so that, should the operator leave the soap in the said recess when the basin is swung upwardly, said soap will be prevented from falling towards the hinged portion of the basin.

The device is simple to operate, as will be seen, means are provided for its safe operation. The device can be folded against a wall and by providing metallic pivot joints in the pipes, the danger of cutting the waste or water connections is reduced to a minimum.

Having thus described my invention, what I claim is:

1. In a folding basin for railway cars and the like, a wash bowl, bracket secured to and depending therefrom, a support extending outwardly from the car body, pivot pins connecting the support to the bracket to allow hinging movement of the bowl water and waste controlling means mounted on the bowl, hot and cold water supply pipes connected to the water controlling means said pipes being connected to a double stop cock, adapted to cut off the water supply when the bowl is in the vertical position, the central pivoting axis of said cock being in alignment with a line passing through the pivot pins, a waste connection having a swivel joint therein in alignment with the axis of

the cock, a waste control lever and means operable by the movement of said lever to lock and unlock the basin.

2. In a folding hand basin pivotally attached to the side of a car, a waste connection having a pivoted joint in alignment with the basin pivot, a waste control lever and means connected to the waste lever to prevent pivoting movement of the basin until the waste pipe is opened to drain water from the bowl.

3. In a folding hand basin having the usual water and waste control levers, said basin being pivotally attached to a wall, means for locking the basin in the horizontal direction when the basin is in use and to unlock said basin when the waste lever is opened to empty the basin.

4. In a folding hand basin having the usual hot and cold water control levers and also waste control levers, means for pivotally connecting the basin to a wall, hot and cold water supply pipes, the outlet from which is controlled by said levers, a double stop cock connected in the hot water and cold water pipe lines, said cock being adapted to cut off the water supply when the basin is raised against the wall, the pivoting axis of said cock being in alignment with the basin pivot, a waste pipe, the outlet to which is controlled by the waste lever, means connected to the waste lever and controlled thereby to lock the basin or unlock same on movement to the waste lever and means to cushion the hinging movement of the basin.

In witness whereof, I have hereunto set my hand.

WALTER E. GORHAM.
